Attorney, Agent, or Firm—George B. Newitt

[57] CLAIM

The ornamental design for a hydrotherapy bath assembly, as shown and described.

DESCRIPTION

FIG. 1 is a perspective view showing one end of the hydrotherapy bath assembly showing my new design;

FIG. 2 is a perspective view showing the other end of the hydrotherapy bath assembly;

FIG. 3 is a top plan view;

FIG. 4 is a side elevational view of one side, the other side elevational view being identical thereto;

FIG. 5 is a view taken along the line 5—5 in FIG. 4;

FIG. 6 is an end elevational view of the one end of the hydrotherapy bath assembly;

FIG. 7 is an end elevational view of the other end of the hydrotherapy bath assembly;

FIG. 8 is a view taken along the line 8—8 in FIG. 4;

FIG. 9 is a bottom plan view.
